[57] CLAIM

The ornamental design for a dancing clown toy, as shown and described.

DESCRIPTION

FIG. 1 is a side elevational view of a dancing clown toy showing my new design, the opposite side being a mirror image;

FIG. 2 is a front elevational view thereof;

FIG. 3 is a sectional view taken along the line 3—3 of FIG. 1;

FIG. 4 is a top plan view thereof; and

FIG. 5 is a side elevational view thereof in an alternate position.

The undisclosed bottom view is unornamented.
